UNITED STATES PATENT OFFICE.

SMITH W. DOUGLAS, OF EUDORA, ARKANSAS.

ROTARY TOOTHBRUSH.

Application filed March 13, 1923. Serial No. 624,754.

To all whom it may concern:

Be it known that I, SMITH W. DOUGLAS, a citizen of the United States, residing at Eudora, in the county of Chicot and State 5 of Arkansas, have invented certain new and useful Improvements in Rotary Toothbrushes; and I do hereby declare the following to be a full, clear, and exact description of the invention, such as will enable 10 others skilled in the art to which it appertains to make and use the same.

This invention relates to a rotary toothbrush.

It is aimed to provide a novel durable 15 structure which enables the bristles to better cleanse and polish the exposed surfaces of and between the teeth by an up and down as well as rotary motion.

Another object is to provide a construction having a novel adjustable protecting means for the mucous membrane of the mouth.

A third object is to provide a novel form 25 of gearing or drive means and mounting casing therefor.

Various additional objects and advantages will become apparent from a consideration of the description following, taken in connection with accompanying drawings illustrating an operative embodiment.

In said drawings:—

Figure 1 is a view of the improved toothbrush in side elevation;

Figure 2 is an edge elevation thereof;

Figure 3 is a central longitudinal sectional view taken on the line 3—3 of Figure 2;

Figure 4 is a central longitudinal sectional view taken on the line 4—4 of Figure 1;

Figure 5 is a transverse sectional view taken on the line 5—5 of Figure 1;

Figure 6 is a detail perspective view of the protector alone;

Figure 7 is a longitudinal sectional view 45 through a modified form, and

Figure 8 is a longitudinal sectional view taken at a right angle to Figure 7 and through the same modified form.

Like reference characters designate like 50 or similar parts in the different views.

Referring specifically to the device of Figures 1 to 7, a brush head 10 is provided which may have an attaching sleeve 11 and bristles or the equivalent at 12. The attaching end of sleeve 11 may be square. Said

end fits a corresponding end portion 13 of a rotary drive shaft 14 friction tight so as to be removable.

A suitable closed protective casing is provided at 15, preferably being generally cylindrical and being in sections 16 and 17 separable from each other along the line 18. The sections 16 and 17 may be held together in any suitable manner and for instance by means of bolts at 19 passing therethrough. At the forward end, sections 16 and 17 have extensions 20 which collectively are cylindrical in order to form a bearing in which shaft 14 is journaled. Longitudinal displacement of the shaft 14 is prevented in any suitable way as for instance by a collar 21 and a bevel gear wheel 22 both carried by said shaft and arranged on opposite sides of and engaging the bearing 20.

Gear wheel 22 meshes with a larger bevel gear wheel 23 located within the casing 15 and keyed to a shaft 24. Shaft 24 is rotatable and also has a pinion or spur gear wheel 25 keyed thereon which meshes with a larger pinion or spur gear wheel 26 keyed to a rotatable shaft 27. A smaller pinion or gear wheel 28 is also keyed to shaft 27 and is adapted to be operated or turned, in order to turn the brush head 10 through the medium of the gearing described, by manual depression of a plunger 29. This plunger has a bar 30 slidably mounted through an opening 31 in the section 17. The bar 30 has a rack or spur teeth at 33 which mesh with the teeth of pinion 28. A button or thumb piece to facilitate manipulation of the plunger is provided at 34. Depression of the bar 30 is accommodated by a dependent receptacle 35 on section 16. This dependent also forms an abutment for the finger to facilitate grasping and effective holding of the casing.

Bar 30 is provided with a lateral lug at 36 through which one end of a power spring 37 is fastened as by rivets 38. The other end of said spring 37 is fastened as by rivets 39 to the section 16. Spring 37 is generally of U-shape and of leaf form tensioned to separate at its attached ends 100 so as to urge the plunger 29 to projected position which movement is limited by the lug 36. Depression of plunger 39 will rotate the gearing so as to rotate the brush head 10 in one direction. After depressing 110

movement, the plunger is released and is restored to uppermost position by spring 37 with the gearing turning the brush head 10 in the opposite direction.

The shafts 24 and 27 are journaled in semicylindrical bearing extensions or flanges 40 and 41 integral with the sections 16 and 17.

The shaft 14 is housed by a tube 42 journaled on the bearing 20 but with sufficient frictional engagement to remain in position to which it may be adjusted. Displacement of the tube 42 is prevented as by a screw or lug 43 carried thereby and extending into an annular groove 44 provided exteriorly on bearing 20. A manipulating arm or thumb piece 45 extends from the sleeve 42. The forward end of tube 42 terminates in a spoon or other shaped protector 46 extending over the brush. Through manipulation of the arm 45, the position of spoon 46 may be varied relatively to the brush head according to the position in which the device is held and in which the brush is working in the mouth. The protector 46 prevents engagement of the brush bristles 12 with the mucous membrane of the mouth and effectively prevents brush head 10 from disengaging shaft 14 in a direction toward the distal end of the brush head. The lumen or passageway of protecting tube 42 is of sufficient caliber to permit it to be slipped off over brush head 10 after loosening said screw 43. This permits removal of the brush head and facilitates cleaning.

In operation, plunger 29 is normally in its projected position where outward movement is limited by engagement of lug 36 with the casing section 17. The casing is held in the hand and the thumb or a finger depresses the button 34 so that the bar 30 is depressed causing teeth 33 to rotate gear wheel 28 and accordingly its shaft 27. Shaft 27 rotates gear wheel 26 which in turn rotates gear wheel 25, shaft 24, gear wheel 23, gear wheel 22 and shaft 14. Shaft 14 rotates the brush head 10 which is disposed in brushing engagement with the teeth. By means of a thumb or a finger, arm 45 may be shifted at will in order to so dispose the protector 46 relative to the bristles 12 that they will not engage the mucous membrane of the mouth. After depression of the button 34, the same is released by the thumb or finger whereupon the spring 37 which has been tensioned through the depression of the plunger, will expand at its open end thus moving the plunger 29 outwardly and rotating the gearing described in the opposite direction. The thumb piece 34 is successively depressed and released which therefore imparts reverse rotary motion to the brush head so that the same will cleanse the teeth through an up and down motion and by the same motion polish

the teeth, as distinguished from horizontal motion as is usually imparted by an ordinary toothbrush.

Various changes may be resorted to within the spirit and scope of the invention. For instance as suggested in Figures 7 and 8, the casing, similar to that at 15 and here designated 50, has an electric motor 51 located therein and adapted to be driven from any suitable source of current under control 75 of an appropriately located switch either on the casing or elsewhere. The main shaft of motor 51 is designated 52 and has a bevel gear wheel 53 keyed thereto which meshes with a bevel gear wheel 54 keyed to a shaft 55 on which a spur gear wheel 56 is also keyed. Gear wheel 56 meshes with a spur gear wheel 57 fastened on a shaft 58 also having a bevel gear wheel 59 fastened thereon. Bevel gear wheel 59 meshes with a bevel gear wheel 60 which may be carried by a shaft 61 which is similar to the shaft 14, mounted in the same way and adapted to drive the brush head 10 in a similar manner. With said motor 51 in operation, through the chain of gearing mentioned, the shaft 61 and accordingly the brush head will be rotated. Shafts 55 and 58 are journaled in the same manner as the shafts 40 and 41 of casing 15. Attention is called to the fact 90 that the gearing in this form is of the speed reducing type since the motor will rotate faster than the brush head should rotate and which is the opposite to the case of the first mentioned form of Figures 1 to 7. 100 Motor 51 may be of any suitable type and if desired may be reversible so that the brush head associated therewith may be rotated in opposite directions alternately as in the case of the form of Figures 1 to 6. 105

I claim as my invention:—

1. A motive apparatus having a casing in sections separable on a plane extending substantially longitudinally thereof, an operating shaft journaled in said casing, split 110 bearings comprising flanges carried by both sections, transverse shafts journaled in said flanges, intermeshing gear wheels on said shafts and on the first mentioned shaft, a compressible operating member engaging one 115 of said gear wheels, and a spring within the casing to return the operating member to normal position having one end fastened to one of the sections and the other end fastened to said operating member. 120

2. A motive apparatus having a casing in sections separable on a plane extending substantially longitudinally thereof, each section having a bearing extension, a rotatable operating shaft journaled in said bearings, bearing flanges on both sections, transverse shafts journaled in said flanges, intermeshing gear wheels on said transverse shafts and first mentioned shaft, means to drive 125 said gear wheels, consisting of a plunger 130

geared to one of the gear wheels, one of the sections having an opening through which the plunger operates, the other section having a dependent receptacle to receive the 5 plunger, and said receptacle also serving as a single abutment, a substantially U-shaped spring within the casing fastened at one end to the section, a lug extending from the plunger adapted to abut the interior of 10 the casing to limit outward movement of the plunger, and the other end of said spring being fastened to said lug.

3. A motive apparatus having a casing in sections separable on a plane extending substantially longitudinally thereof, each section having a bearing extension, a rotatable operating shaft journaled in said bearings, bearing flanges on each section, transverse

shafts journaled in said flanges, intermeshing gear wheels on said transverse shafts 20 and first mentioned shaft, means to drive said gear wheels, consisting of a plunger geared to one of the gear wheels, one of the sections having an opening through which the plunger operates, the other section having a dependent receptacle to receive the 25 plunger, and said receptacle also serving as a single abutment, a substantially U-shaped spring within the casing fastened at one end to the section, a lug extending from the 30 plunger adapted to abut the interior of the casing to limit outward movement of the plunger, and the other end of said spring being fastened to said lug.

In testimony whereof I affix my signature.
SMITH W. DOUGLAS.
